Fred Hirsh, New York, N. Y., assignor to Adjusta
Company, a corporation of New York

Application June 29, 1934, Serial No. 52,396

Term of patent 7 years

To all whom it may concern:

Be it known that I, FRED HIRSH, a citizen of the United States, residing in the city of New York, in the county of New York and State of New York, have invented a new, original, and ornamental Design for a Buckle, of which the following is a specification, reference being had to the accompanying drawing, forming part thereof, in which:

I claim:

The ornamental design for a buckle as shown.

FRED HIRSH.
